POCKET DICTATING MACHINE

Rebertus Van der Poel, Eindhoven, Netherlands, assignor
to North American Philips Co., Inc.

Filed May 23, 1967, Ser. No. 7,243

Claims priority, application Switzerland Dec. 30, 1966

Term of patent 14 years

(Cl. D26—14)

FIG. 1

FIG. 2

FIG. 1 is a perspective view of the pocket dictating machine, showing my design;

FIG. 2 is a perspective view in the loading or unloading position;

FIG. 3 is an elevational view of FIG. 1 inverted;

FIG. 4 is an elevational view of the opposite side thereof;

FIGS. 5 and 6 are right and left end views respectively of FIG. 1 inverted;

FIGS. 7 and 8 are top and bottom plan views respectively of FIG. 1.

The dominant features reside in the solid line portions. I claim:

The ornamental design for a pocket dictating machine, as shown and described.
